United States Patent Office

THOMAS DOLAN, OF PHILADELPHIA, PENNSYLVANIA.

Design No. 4,976, dated June 6, 1871.

DESIGN FOR A STOCKING FABRIC.

The Schedule referred to in these Letters Patent and making part of the same.

I, THOMAS DOLAN, of Philadelphia, county of Philadelphia, State of Pennsylvania, have invented or produced a Design for a Stocking Fabric, of which the following is a specification.

The figure in the accompanying drawings represents my design for a stocking fabric, the principal features of which are the two main stripes A and A', each composed of bars, as shown, and the intermediate narrow stripe B, of the character represented.

Above the stripe A are two narrow stripes, C and C', and below the stripe A' a similar narrow stripe, C'.

Between the stripes C and C' is a series of plain ribs, a, and below the stripe C' another series of plain ribs, b.

Irrespective of the colors employed,
I claim—

The design for a stocking fabric, substantially described and as represented in and by the accompanying drawings.

In testimony whereof I have signed my name to this specification in the presence of two subscribing witnesses.

THOMAS DOLAN.
